UNITED STATES PATENT OFFICE.

WILLARD T. SEARS, OF BROOKLYN, NEW YORK, ASSIGNOR TO NILES-BEMENT-POND COMPANY, OF NEW YORK, N. Y., A CORPORATION OF NEW JERSEY.

RADIAL DRILLING-MACHINE.

1,365,009.

Specification of Letters Patent. Patented Jan. 11, 1921.

Application filed October 1, 1918. Serial No. 256,430.

To all whom it may concern:

Be it known that I, WILLARD T. SEARS, a citizen of the United States, residing at Brooklyn, in the county of Kings and State 5 of New York, have invented certain new and useful Improvements in Radial Drilling-Machines, of which the following is a specification.

One object of the invention is to provide 10 an improved unit system of construction for radial drilling machines whereby certain new and important advantages are secured. In accordance with my invention I am able to provide either a full universal or a semi- 15 universal radial drill and I am able to provide either a variable-speed-motor driving mechanism or a constant-speed-motor driving mechanism. It is possible to provide these different forms of machines without 20 changing the construction of the greater part of the drill mechanism, and in this way the cost is reduced to a minimum. A further object of the invention is to provide 25 an improved construction for the frame which supports the arm, the motor and other parts.

In the accompanying drawings which illustrate the preferred embodiment of the invention:

30 Figure 1 is a side view of a full universal radial drilling machine having a variable-speed-motor driving mechanism.

Fig. 2 is a fragmentary vertical sectional view of the drilling machine shown in 35 Fig. 1.

Fig. 3 is a fragmentary horizontal view, partly in section, of the mechanism shown in Fig. 2.

Fig. 4 is a fragmentary vertical sectional 40 view in some respects similar to Fig. 2 but showing a semi-universal radial drilling machine with a constant-speed-motor driving mechanism.

Fig. 5 is a fragmentary plan view, partly 45 in section, of the mechanism shown in Fig. 4.

Fig. 6 is a detail view taken on the line 6—6 of Fig. 4 looking in the direction of the arrow and showing two of the driving 50 gears for the drilling machine.

As concerns the general arrangement of parts, a drilling machine embodying the present invention is similar to that set forth in my patent for radial drills No. 1,071,590 55 dated August 26th, 1913. As illustrated, the

machine comprises a base, preferably made up of two parts 1 and 2. Mounted on the part 2 of the base is a column 3 which is preferably divided vertically into two similar parts 3^a and 3^b. The column can be 60 moved with respect to the base about a vertical pivotal axis and preferably the column is provided at 4 with a broad supporting surface which engages a companion surface on the base part 2. Suitable bearings for 65 the column are provided within the base part 2 and I prefer to provide a mechanism such as that set forth in my co-pending application for supporting and clamping mechanism for drilling machines, 70 Serial No. 229,999 filed April 22nd, 1918. As illustrated, there is provided a ball-bearing 5 at or near the center of the column which assists in supporting the column, and there is provided a roller bearing 6 which serves 75 to hold the column in position and prevent its movement away from the vertical. A suitable clamping mechanism is provided which is operated by a lever 7. When the column is clamped by the said clamping 80 mechanism the supporting surface 4 engages the corresponding surface of the base part 2, thus providing a broad flat direct and rigid support for the column.

There are provided two optionally usable 85 frame and arm mechanisms either of which may be associated with the column 3. One of these mechanisms is adapted to form a part of a full universal radial drilling machine in which the arm is adjustable about a 90 horizontal axis and the other mechanism is adapted to form a part of a plain radial drilling machine in which the arm is held against movement about a horizontal axis. One of the said column and arm mechanisms is shown in Figs. 1 to 3 and the other 95 is shown in Figs. 4 and 5.

Referring first to Figs. 1 to 3, it will be seen that a supporting frame 8 is guided for vertical movement between the two parts 100 3^a and 3^b of the column. The frame construction is in some respects similar to that shown in my patent for radial drills, No. 1,076,242 dated October 21st, 1913 but has important features of improvement. As 105 illustrated, the frame 8 is provided at one end with a flange having inclined surfaces 9, 9 which engage similarly inclined surfaces on the corresponding edges of the column parts. The other end of the frame is 110

sufficiently narrow to permit the frame to be moved endwise into position between the column parts. At the narrow end of the frame there are provided gibs 10, 10 having 5 inclined surfaces which engage similarly inclined surfaces on the corresponding edges of the column parts. Bolts 11, 11 are provided for holding the gibs 10, 10 in place and these bolts are adjusted to bring the 10 gibs into working relation with the corresponding surfaces of the column parts without, however, effecting such a clamping action as would interfere with the free vertical movement of the frame.

15 Formed at one side of the frame 8 is a vertical flange 12 which is provided with circular guiding surfaces adapted to be engaged by parts of the drill arm. As illustrated, these circular guiding surfaces are 20 the walls of a circular T-slot 13 formed in the flange 12. The drill arm is illustrated at 14 and this arm is provided with an annular tongue 15 adapted to enter the slot 13 and engage the guiding surfaces at the edges 25 thereof. T-bolts 16—16 extend into the T-slot 13 and serve to hold the arm in place with respect to the frame. When the bolts are loosened the arm can be turned about a horizontal axis and when the bolts are tightened 30 the arm is clamped against such movement. Preferably for turning the arm there is provided a worm wheel 17 secured to the arm and a worm 18 meshing with the worm wheel carried by the frame 8. The worm 18 35 is mounted on a shaft 19 having a squared end whereby the worm may be rotated to effect turning of the arm.

The second frame and arm mechanism, as 40 illustrated in Figs. 4 and 5, includes a supporting frame 8^a which is the same as the frame 8 except that it is not provided with a circular vertical flange 12. The same gibs 10 and associated parts are used for the frame 8^a. The frame 8^a is provided with a 45 flange 12^a having a vertical surface adapted to be engaged by a similar surface of an arm 14^a. The arm 14^a is similar to the arm 14 but is not provided with a circular tongue 15 or with a worm wheel 17. Instead it is 50 provided with a flat surface adapted to engage the flat surface of the flange 12^a. By means of bolts 16^a—16^a the arm 14^a can be rigidly secured to the frame 8^a and held 55 against any movement about a horizontal axis.

For adjusting either of the supporting frames vertically there is provided a mechanism of the type set forth in my patent for adjusting mechanism No. 1,122,649 dated 60 December 29th, 1914. As concerns the more specific features, I prefer a mechanism such as set forth in my copending application for adjusting mechanism for drilling machines, Serial No. 229,998, filed April 22nd, 1918. 65 For effecting vertical adjustment there is

provided a vertical screw 20, which is normally fixed against rotation, and a nut 21 which engages the screw and is adapted to be turned preferably by power. Secured to the screw 20 at its upper end is a conical 70 member 22 having a concave conical surface which engages a convex conical surface on a plate 23 secured to the top of the column. The frictional engagement of the two conical surfaces normally prevents the screw from 75 turning, but nevertheless permits the screw to turn when necessary to protect the machine from injury. The nut 21 is fitted in a bearing 24 secured to the supporting frame, and preferably a ball-bearing 25 is provided 80 between the nut and the bearing 24 whereby the weight of the frame and of the associated parts may be transmitted to the nut. Connected with the nut 21 is a bevel gear 26 which meshes with a bevel gear 27 on a horizontal shaft 28. When the shaft 28 is rotated in the manner to be presently described, the nut 21 is turned with respect to the screw 20, thus causing the supporting frame with the associated parts to move upward or downward along the column.

After the supporting frame has been adjusted to the proper elevation it can be clamped by means of bolts 29, 29 which extend across the frame and through the gibs 95 10, 10. Engaging these bolts 29, 29 are nuts provided with operating levers 30, 30. By means of these levers the bolts 29, 29 can be tightened to draw the gibs 10, 10 toward each other and thus force them into firm engagement with the inclined surfaces of the column parts so as to clamp the frame against movement.

Adapted to fit either of the arms 14 or 14^a and to be horizontally movable along either 105 of them is a saddle 31 carrying a drill head 32. The drill head is preferably angularly adjustable with respect to the saddle so that the spindle 33 thereof can be positioned at any angle.

Secured to whichever of the supporting frames 8 and 8^a that is in use, is a housing 34. Connected with the drill head 32 is a train of elements for transmitting power to rotate the spindle. This train is adapted 115 to be associated with either one of the frame and arm mechanisms and it includes a horizontal shaft 35 extending longitudinally of the arm. This shaft is so located that, when the frame and arm mechanism shown in 120 Figs. 1 to 3 is used, its axis is coincident with the axis of movement of the arm 14. Suitable devices, such as are well known in the art, connect the shaft 35 with the spindle 33 and with other parts of the drill head 32.

The power transmitting train preferably 125 also includes suitable gearing located in the housing 34. As illustrated, there is a driving sleeve 36 surrounding the shaft 35 and rotatable with respect thereto, this sleeve 130

fitting a suitable bearing in the wall of the housing. Removably mounted on the sleeve 36 is a gear 37, and also mounted on the sleeve is a pinion 38. The pinion 38 meshes 5 with a gear 39 on a countershaft 40. The shaft 40 also carries a pinion 41 which is adapted to mesh with a gear 42 splined on the shaft 35. When the gear 42 is in the position shown, power can be transmitted 10 from the driving sleeve 36 through the gears 38, 39, 41 and 42 to rotate the shaft 35 at a relatively slow speed. Connected with the gear 42 is a grooved collar 43 with which is associated a forked lever 44. By means of 15 a hand lever 45 the lever 44 can be moved to shift the gear 42 out of mesh with the pinion 41. The pinion 38 and the gear 42 are provided with clutch teeth adapted to engage each other, and when the gear 42 is moved toward the left out of mesh with the pinion 41 these teeth are engaged and power 20 is then transmitted directly from the driving sleeve 36 to rotate the shaft 35 at a relatively high speed.

25 Preferably the shaft 40 is in longitudinal alignment with the aforesaid shaft 28 and a clutch is provided at 46 whereby the two shafts may be connected to transmit power to rotate the nut 21. The clutch 46 is adapted to be operated by a hand lever 47.

I provide two optionally usable power mechanisms, either of which may be secured to the housing 34 to engage the gear 37 and thus transmit power to the driving sleeve 36 35 and to the aforesaid power transmitting train which is connected with the drill head. One of these mechanisms is shown in Figs. 1 to 3 and the other of them is shown in Figs. 4 and 5. It will be understood that 40 either of these mechanisms may be used in accordance with the conditions which are encountered, and it will further be understood that the conditions which determine the selection of one or the other of the frame 45 and arm mechanisms may be quite independent of the conditions which determine the selection of one or the other of the power mechanisms. Therefore either of the power mechanisms may be used with either of the frame and arm mechanisms. The particular relationships shown in the drawings are selected merely for purposes of illustration, and it will be understood that other relationships may be employed.

55 Referring first to the power mechanism shown in Figs. 1 to 3, it will be observed that there is a bracket 48 which is bolted directly to the housing 34. Suspended from the bracket is a motor 49 which carries a 60 pinion 50 meshing with the aforesaid gear 37 on the driving sleeve 36. The motor 49 is of the variable-speed type, being under the control of a suitable controller which is indicated at 51, but which is not shown 65 in detail as it of itself constitutes no part

of the invention. The motor 49 is adapted to be operated on direct current and when direct current is available the power mechanism shown in Figs. 1 to 3 will ordinarily be used. 70

When the drill is to be operated on alternating current, use will ordinarily be made of the power mechanism shown in Figs. 4 and 5. This mechanism comprises a bracket 48^a which is directly bolted to the housing 75 34. Mounted on this bracket is a motor 49^a which is of the constant-speed type and is adapted to be operated on alternating current. Carried on the bracket 48^a is a suitable change-speed mechanism which is indicated in a general way at 52, the bracket being preferably constructed in box-like form to inclose the said mechanism. This mechanism does not of itself constitute a part of the present invention, it being set forth in 80 my co-pending application for change-speed mechanism, Serial No. 260,224 filed Oct. 30, 1918. For present purposes it is sufficient to point out that this mechanism includes a pinion 50^a which is adapted to mesh with a 90 gear 37^a adapted to be mounted on the driving sleeve 36 in lieu of the gear 37. Power is transmitted to the change-speed mechanism from the motor 49^a and by moving the hand lever 53 the mechanism 52 can be adjusted to change the speed of the final pinion 50^a, and thus change the speed of the 95 drill spindle 33.

The two power mechanisms are so constructed as to have approximately the same 100 balancing effect with respect to the arm and head, and the general arrangement of parts is such that with either power mechanism in place the combined center of gravity of the column and all of the parts carried thereby will be at or near the center of the 105 column.

The constant-speed motor 49^a is considerably lighter than the variable-speed motor 49, and this smaller motor weight approximately compensates for the greater weight of the bracket 48^a and the change-speed mechanism 52 carried thereby. The combined center of gravity will change somewhat when the saddle and head are moved 110 along the arm, but preferably it will always remain within the outline of the broad supporting surface 4 at the bottom of the column 3. The roller bearing 6 serves to resist any tendency for the column to move 115 away from the vertical position, but it will be obvious that the frictional resistance offered by this bearing will be at a minimum when the center of gravity is close to the column axis. 120

125 What I claim is:

1. A system of radial drill construction, comprising a base, a vertically divided column mounted on the base for movement about a vertical axis, two optionally usable 130

- frame and arm mechanisms, one mechanism consisting of a supporting frame vertically movable along the column between the parts thereof and an arm connected with the 5 frame for movement about a horizontal axis and the other mechanism consisting of a vertically movable supporting frame similar to the first said frame and an arm rigidly secured to the frame and held against movement about a horizontal axis, a horizontally movable saddle and drill head adapted to be carried by either arm, a housing secured to the frame at the side of the column opposite the arm, an electric motor secured to the 10 housing, and a power transmitting train adapted to connect the motor and the drill head, the said train being operative with either arm mechanism in place.
2. A system of radial drill construction, 20 comprising a base, a vertically divided column mounted on the base for movement about a vertical axis, two optionally usable frame and arm mechanisms, one mechanism consisting of a vertically movable supporting frame vertically movable along the column between the parts thereof and provided with circular guide surfaces at one side and an arm engaging the circular guide surfaces of the frame and connected for movement about a horizontal axis and the other mechanism consisting of a vertically movable supporting frame similar to the first said frame but without circular guide surfaces and an arm rigidly secured to the 25 frame and held against movement about a horizontal axis, mechanism located between the column parts and coöperative with either frame for moving it vertically, a horizontally movable saddle and drill head adapted to be carried by either arm, a housing secured to the frame at the side of the column opposite the arm, an electric motor secured to the housing, and a power transmitting train adapted to connect the motor and the 30 drill head, the said train being operative with either arm mechanism in place.
3. A system of radial drill construction, 35 comprising a base, a column mounted on the base for movement about a vertical axis and having a horizontal base-engaging supporting surface, a supporting frame vertically movable along the column, an arm carried by the frame at one side of the column, a drill head carried by the arm, a housing secured to the frame at the other side of the column, a power transmitting train connected with the drill head and including gearing in the housing, and two optionally usable power mechanisms each adapted to be detachably secured to the housing, one mechanism consisting of a bracket and a variable-speed electric motor on the bracket adapted to connect with the said power transmitting train for transmitting power through the change-speed gearing to the aforesaid power transmitting train, the two said mechanisms being so constructed and arranged that the balancing effect with respect to the arm and head will be approximately the same with either mechanism secured to the housing whereby the combined center of gravity of the column and all parts carried thereby is maintained within the outline of the aforesaid supporting surface of the column.
4. A system of radial drill construction, 40 comprising a base, a vertically divided column mounted on the base for movement about a vertical axis and having a horizontal base-engaging supporting surface, a supporting frame vertically movable along the column between the parts thereof, an arm carried by the frame at one side of the column, a drill head carried by the arm, a housing secured to the frame at the other side of the column, a power transmitting train connected with the drill head and including gearing in the housing and a shaft extending longitudinally of the arm and passing between the divided parts of the column, and two optionally usable power mechanisms each adapted to be detachably secured to the housing, one mechanism consisting of a bracket and a variable-speed electric motor on the bracket adapted to connect with the said power transmitting train for transmitting power thereto and the other mechanism consisting of a bracket, change-speed gearing on the bracket adapted to connect with the said power transmitting train and a constant-speed electric motor on the bracket for transmitting power through the change-speed gearing to the aforesaid power transmitting train, the two said mechanisms being so constructed and arranged that the balancing effect with respect to the arm and head will be approximately the same with either mechanism secured to the housing whereby the combined center of gravity of the column and all parts carried thereby is maintained within the outline of the aforesaid supporting surface of the column.
5. A system of radial drill construction, 45 comprising a base, a column mounted on the base for movement about a vertical axis and having a horizontal base-engaging supporting surface, two optionally usable frame and arm mechanisms, one mechanism consisting of a supporting frame vertically movable along the column and an arm connected with the frame for movement about a horizontal axis and the other mechanism consisting of a vertically movable supporting frame similar to the first said frame and thereto and the other mechanism consisting

- an arm rigidly secured to the frame and held against movement about a horizontal axis, a horizontally movable saddle and drill head adapted to be carried by either arm, 5 a housing secured to the frame at the side of the column opposite the arm, a power transmitting train connected with the drill head and including gearing in the housing, and two optionally usable power mechanisms each adapted to be detachably secured to the housing, one mechanism consisting of a bracket and a variable-speed electric motor on the bracket adapted to connect with the said power transmitting train for transmitting power thereto and the other mechanism consisting of a bracket, change-speed gearing on the bracket adapted to connect with the said power transmitting train and a constant-speed electric motor on the bracket for transmitting power through the change-speed gearing to the aforesaid power transmitting train, the two said mechanisms being so constructed and arranged that the balancing effect with respect to the arm and head will be approximately the same with 10 15 20 25
- either mechanism secured to the housing, whereby the combined center of gravity of the column and all parts carried thereby is maintained within the outline of the aforesaid supporting surface of the column. 30
6. In a radial drilling machine, the combination of a vertically divided column, a vertically movable supporting frame positioned between the parts of the column and having a flange at one end adapted to engage the corresponding edges of the column parts, the other end of the frame being sufficiently narrow to permit the frame to be moved endwise into position between the column parts, gibs adapted to be secured to 35 the frame at the narrow end and to engage the corresponding edges of the column, an arm carried by the frame at the first said end, a drill head on the arm, and a motor bracket and motor carried by the arm at 40 45 the second said end.

In testimony whereof, I hereto affix my signature.

WILLARD T. SEARS.
